UNITED STATES PATENT OFFICE.

BESSIE MILLS NYE, OF ARVADA, COLORADO.

DESIGN FOR A DOLL.

Application filed January 22, 1924. Serial No. 8,370. Term of patent 7 years.

To all whom it may concern:

Be it known that I, BESSIE MILLS NYE, a citizen of the United States, residing at Arvada, in the county of Jefferson and State of Colorado, have invented a new, original, and ornamental Design for a Doll, as shown in the accompanying drawing and described in the following specification.

Fig. 1 is a front elevation of the improved doll and Fig. 2 is a back elevation of the same.

I claim:

The ornamental design for a doll substantially as shown.

BESSIE MILLS NYE.
